UNITED STATES PATENT OFFICE.

ANDREW J. THOMPSON, OF ALTON, NEW HAMPSHIRE.

STEAM-TURBINE.

1,345,285.

Specification of Letters Patent. Patented June 29, 1920.

Application filed January 31, 1917, Serial No. 145,715. Renewed December 6, 1919. Serial No. 343,113.

To all whom it may concern:

Be it known that I, ANDREW J. THOMPSON, a citizen of the United States, residing at Alton, in the county of Belknap and State of New Hampshire, have invented new and useful Improvements in Steam-Turbines, of which the following is a specification.

This invention relates to improvements in elastic fluid turbines and has particular application to a movable stage turbine.

In carrying out the present invention, it is my purpose to provide a movable stage elastic fluid turbine wherein the elastic fluid will be successively directed against the turbine wheels in order to rotate such wheels and the shaft upon which the wheels are mounted, thereby enabling the fluid motive force to be transformed into mechanical power.

It is also my purpose to provide an elastic fluid turbine wherein the elastic fluid may be directed against the turbine wheels in either direction so that the direction of rotation of the shaft may be reversed.

Another object of my invention is the provision of an elastic fluid turbine which will embrace the desired features of simplicity, efficiency, and durability, which may be installed and maintained at small cost, and which will embody comparatively few parts and these so arranged and correlated as to reduce the possibility of derangement to a minimum.

With the above and other objects in view, the invention consists in the construction, combination, and arrangement of parts hereinafter set forth and falling within the scope of the claims.

In the accompanying drawings:—

Figure 1 is a view in side elevation of a movable stage elastic fluid turbine constructed in accordance with the present invention.

Fig. 2 is a longitudinal sectional view through the same.

Figs. 3, 4, and 5 are views of details of the invention.

Referring now to the drawings in detail, 1 designates a cylindrical casing formed of two semi-circular sections having their meeting edges equipped with outturned flanges 2 provided with alining bolt holes that receive securing bolts 3, whereby the semi-circular sections may be held in casing formation. 4—4 designate end castings that close the ends of the casing 1 and have the inner ends formed with outwardly extending

flanges 5 that abut similar flanges 6 formed on the respective ends of the casing 1. Through these flanges 5 and 6 are passed securing bolts 7 whereby the end castings 4 60 may be securely held to the casing 1 to close the ends of such casing. The end castings 4 are equipped with axially alining bearings 8 arranged concentrically of the longitudinal axis of the casing 1, and rotatably mounted 65 in these bearings 8 is a shaft 9 that extends through the end castings 4 and the casing 1.

In the present instance, each casting 4, adjacent to the inner end thereof, is formed with an annular shoulder 10. Arranged 70 within the casing 1 is a cylinder 12 and surrounding said cylinder and in contact therewith is an open ended cylindrical shell 11 having the ends in engagement with the shoulders 10 so that longitudinal movement 75 of the shell 11 within the casing 1 is prevented. The shell 11 acts as a packing to prevent leakage of steam from the screw holes in the cylinder 12 to the joint between the casing 1 and the ends thereof. Arranged 80 concentrically of the shaft 9 and disposed within the cylinder 12 are disk-like abutments 13 spaced apart equal distances along the shaft and having the peripheries thereof in engagement with the inner surface of the 85 cylinder 12. These abutments 13 are stationary and are fastened to the cylinder 12 by means of screws 14 or other fastening elements that are passed through the cylinder 12 and into the peripheral edges of the abutments. Arranged within the spaces between the abutments, respectively, are turbine 90 wheels 15 that are disposed concentrically of the shaft 9 and fastened through the peripheries of the abutments 13 and formed with 95 diagonal blades 16 while the peripheries of the turbine wheels 15 are formed with transverse blades 17.

The end castings 4 constitute steam chests and leading from the bottom of each steam 100 chest and in open communication therewith is a pipe line 18. The outer ends of the pipe lines 18 are connected with a two-way valve 19 that has one side connected with a steam supply pipe 20 and the other side provided 105 with an exhaust port 21.

In practice, when the two-way valve 19 is in one position steam flows from the supply pipe 20 through one pipe line 18 into one of the steam chests formed by the castings 4, and after the steam enters the steam chest such steam flows through the

- spaces between the blades 16 of the end abutment 13 and is directed against the blade 17 of the adjacent turbine wheel 15, thereby imparting movement to the turbine 5 wheel, the steam continuing to pass through the successive abutments and turbine wheels to the steam chest at the opposite end of the cylinder 12, and then exhausting to the atmosphere, through the other pipe line 18, 10 the two-way valve, and the port 21. Thus as the steam passes through the abutments and turbine wheels successively, such steam acts upon the turbine wheels to rotate the latter and the shaft 9, thereby converting 15 the motive power of the elastic fluid into mechanical power. To reverse the turbine, it is only necessary to reverse the position of the two-way valve and when this is done the former live steam chest becomes the exhaust 20 steam chest while the first exhaust steam chest becomes the live steam chest, thereby causing the steam to flow through the abutments and the turbine wheels successively in the reverse direction.
- 25 It will be noted that the pipe lines 18 connect with the respective steam chests at the lower ends of the latter so that any water of condensation in the steam chest may be drained off. In this embodiment of 30 my invention, the confronting surfaces of the abutments and the turbine wheels are formed with coöperating grooves to receive packing 22 in order to prevent leakage. The bearings 8 are connected with suitable 35 brackets 23 so that the turbine engine may be appropriately supported. The stem of the two-way valve 19 is equipped with a handle 24 whereby the valve may be operated.
- 40 While I have herein shown and described the preferred form of my invention by way of illustration, I wish it to be understood that I do not limit or confine myself to the precise details of construction herein described and delineated, as modification and 45 variation may be made within the scope of the claims and without departing from the spirit of the invention.
- I claim:—
- 50 1. An elastic fluid turbine comprising an open ended cylindrical casing, castings closing the ends of said casing and acting in the capacity of steam chests, bearings carried by said castings respectively and alining 55 with each other, a shaft journaled in said bearings, stationary abutments arranged concentrically of said shaft within said casing, and spaced apart equal distances, turbine wheels arranged within the spaces respectively between said abutments and fixed 60 upon said shaft, steam pipes connected with said steam chests respectively at the lower ends thereof, a source of supply, a two-way valve for connecting one of said steam pipes with said source of supply, and the other of 65 said pipes with the atmosphere and vice versa whereby the steam may be directed through the abutments and turbine wheels successively in either direction to rotate said 70 shaft, a cylinder within said casing surrounding said abutments and wheels, fasteners connecting said abutments to said cylinder, and a shell surrounding said cylinder between the latter and said casing and covering said fasteners. 75
2. An elastic fluid turbine comprising an open ended cylindrical casing, castings closing the ends of said casing and acting in the capacity of steam chests, bearings carried by said castings respectively and alining 80 with each other, a shaft journaled in said bearings, stationary abutments arranged concentrically of said shaft within said casing and spaced apart equal distances, turbine wheels arranged within the spaces respectively between said abutments and fixed 85 upon said shaft, steam pipes connected with said steam chests respectively at the lower end thereof, a source of supply, a two-way valve for connecting one of said steam pipes 90 with said source of supply and the other of said pipes with the atmosphere and vice versa whereby the steam may be directed through the abutments and turbine wheels successively in either direction to rotate said 95 shaft, a cylinder within said casing surrounding said abutments and wheels and connected to said abutments to hold the latter stationary, fasteners connecting said abutments and cylinder, a shell surrounding 100 said cylinder between the latter and said casing and covering said fasteners, and shoulders formed on the inner walls of said castings adjacent to the inner ends of the latter and acting to hold said shell and cylinder in proper position within said casing. 105
- In testimony whereof I affix my signature.
- ANDREW J. THOMPSON.
